D. Anthony Keina

UNITED STATES PATENT OFFICE.

STANLEY M. RUMBOUGH, OF NEW YORK, N. Y.

CAP.

Application filed November 25, 1924. Serial No. 752,079.

My invention aims to provide an improved means for securing caps to the outlets of collapsible tubes, sprinkler tops and other receptacles. An embodiment of the invention is illustrated in the accompanying drawings in which

Fig. 1 is an enlarged elevation of the upper portion of a collapsible tube with a cap secured thereto in closed position;

10 Fig. 2 is an elevation from the right side of Fig. 1;

Fig. 3 is an elevation viewed in the same direction as Fig. 1 but showing the cap in open position;

15 Fig. 4 is a view showing the parts before their assembly;

Fig. 5 is a detail view of an improved hinge member.

Referring to the embodiment of the invention illustrated the collapsible tube 10 is provided with a screw threaded neck 12 having a retaining ring 14 screwed thereon. The cap 16 also engages the screw threads of the neck 12 but is provided with means whereby it cannot be separated from the tube 10 when fully unscrewed from the neck 12 thereof. The neck 12 is provided with a plain cylindrical portion 18 and the retainer ring 14 is provided with an inwardly extending flange 20 which is adapted to limit the endwise movement of the retaining ring so as to prevent its being unscrewed entirely from the cap, the flange 20 being adapted to engage a shoulder 22 formed by the metal of the screw threads overhanging the plain cylindrical portion 18 of the neck.

The cap 16 is hingedly secured to the retaining ring 14 by an improved connecting member comprising a hinge link 24 of substantially rectangular shape as shown in Fig. 5. This link is provided with pintle portions 26 and 28 which are connected by leg members 30. The cap 16 is formed with an outwardly extending lug 32 which in its initial stage of manufacture extends straight outwardly as illustrated in Fig. 4. The retainer ring 14 is formed with a similar outwardly extending lug 34. In assembling the parts the hinge link 24 is slipped over the outer ends of the projections 32 and 34 and the latter are bent around as indicated at 36 and 38 so as to form pivot bearings for the pintle portions 26 and 28 respectively of the hinge link 24. The length of the projections 32 and 34 is such that when they are bent around to the position shown in Fig. 1

their ends will engage the body portions of the cap retaining ring and provide sufficient clearance to permit the hinge link to swing freely thereon.

60 This form of link is an improvement over an ordinary hinge pin. It provides for greater freedom of movement between the cap and the retaining ring and enables the formation of a hinge connection without the necessity of drilling holes in either the cap or the retaining ring. This is an important consideration in manufacture of articles of this class in which the cost of the container must be kept to a minimum. A further advantage of connecting the cap to the retainer ring by means of a floating hinge link is that such a connection makes it unnecessary to form the parts with extreme accuracy in order to permit the cap and the retaining 75 ring to be aligned with the screw threaded neck. It will be appreciated that the floating hinge link described will permit the cap to have considerable lateral play relative to the retainer ring thus making it an 80 easy matter to engage the screw threads of the cap with those of the threaded neck of the tube. It will be readily apparent that if the cap were secured by a rigid hinge pin to the retainer that the relationship of the 85 parts must be very accurate in order that they can be properly screwed onto the neck of the tube. With this in mind it will be appreciated that extreme accuracy would be required in locating the holes for the rigid 90 pintle pins of an ordinary hinge connection. On the other hand, because of the play allowed by the employment of a floating hinge link as above described it is appreciated that 95 extreme accuracy in manufacture is not necessary and hence the cost of producing caps according to my invention is materially less than the cost of manufacturing caps heretofore used.

100 Though I have described with great particularity of detail certain embodiments of the invention, it is not to be understood therefrom that the invention is restricted to the particular embodiments disclosed. Various modifications in detail and in the arrangement of the parts may be made by those skilled in the art without departure from the invention as defined in the following claims.

110 What I claim is;

1. A container having a threaded neck, a cap adapted to be screwed thereon, a retain-

er swivelled on said container, and a hinge link having spaced pintle portions pivotally engaging integral projections formed on the cap and retainer respectively.

5. 2. A container having a threaded neck in combination with a cap screwed thereon, a retainer swiveled on said neck adapted to permit the cap to be swung to open position without detachment and a hinge member having spaced pintle portions engaging the cap and retainer respectively.
- 10 3. A container having a threaded neck in

combination with a cap screwed thereon, a retainer swiveled on said neck adapted to permit the cap to be swung to open position without detachment and a hinge link of substantially rectangular form having portions forming spaced pintles, and lugs formed on said cap and said retainer bent to engage said pintle portions, substantially as described. 15

In witness whereof, I have hereunto signed my name.

STANLEY M. RUMBOUGH.
